REGISTERING MONEY BANK

Robert B. Hayden, Seattle, Wash., assignor to
 H. L. J. Specialty Co., Seattle, Wash., a corpora-
 tion of Washington

Application January 6, 1932, Serial No. 585,034

7 Claims. (Cl. 235—100)

My invention relates to improvements in money banks for the reception of coins and my present invention is in the nature of an improvement on the bank disclosed in my prior Patent 5 Number 1,826,398, issued October 6, 1931.

The general objects of my invention are to improve and simplify the construction of banks of this nature and to reduce the cost of manufacture of said banks and render said banks more reliable and efficient in operation.

More specific objects are to provide a small savings bank which may be given out by savings institutions to depositors, said savings bank having a plurality of coin slots for the insertion of 15 coins of different denomination and further having registering means operated by the insertion of the coins for registering, totaling and visibly indicating, within certain limits, the amounts of the coins of each denomination which have been 20 inserted through the respective slots, said mechanism embodying devices for precluding the operation of the registering means except by the insertion of a proper coin and devices for preventing the extraction of the coins after they have 25 been inserted far enough into the registering means to operate the same.

A still further object is to provide a registering bank of this nature in which the registering mechanism is all secured to the cover of the bank 30 and removable with said cover thereby leaving said registering mechanism readily accessible for the purpose of re-setting the same when the bank is opened.

Other and more specific objects will be apparent from the following description taken in connection with the accompanying drawing.

In the drawing Figure 1 is a view partly in section and partly in plan substantially on broken 40 line 1—1 of Fig. 2 of a registering bank constructed in accordance with my invention.

Fig. 2 is a section substantially on broken line 2—2 of Fig. 1.

Fig. 3 is a detached perspective of a main frame 45 member.

Fig. 4 is a detached plan showing a plurality of pawl and slide members with a locking plate positioned thereon.

Fig. 5 is an edge view of the parts shown in 50 Fig. 4.

Fig. 6 is a detached elevation of a register wheel.

Fig. 7 is a sectional view of one register wheel showing it operatively positioned with respect to 55 a fragment of another wheel.

Fig. 8 is a fragmentary elevation of two register wheels and a stop and friction spring therefor.

Fig. 9 is a fragmentary plan of a numbered strip used on the periphery of the register wheels.

Fig. 10 is a cross section of the cover on line 10—10 of Fig. 2.

Fig. 11 is a detached plan view of a fragment of a resilient plate used to prevent withdrawal of the coins after they are partly inserted.

Like reference numerals designate like parts 10 throughout the drawing.

In accordance with my present invention I provide a receptacle 10, preferably of rectangular shape and open at the top. A shallow rectangular cover 11 is provided for closing the open top of receptacle 10, said cover 11 having a downwardly extending inwardly offset lip 12 at one end arranged to fit within the receptacle. The lip 12 extends around the corners and for a short distance along the sides of the cover 11, see dotted 20 lines Fig. 2, and the other end of cover 11 is secured to the housing 10 by a lock 13 having a throw 14 operable by a key, not shown, which may be inserted through a keyhole 15. A plurality of catch lugs 16, preferably three, are 25 formed in each end of receptacle 10 by punching inwardly portions of the metal at the top edge. Lip 12 of cover 11 has recesses 17 formed therein, which fit over said lugs 16 at one end and the throw 14 engages with one of said lugs 16 at 30 the other end. The provision of the lugs 16 at both ends makes it possible to have the cover 11 reversible on the receptacle 10, thus making it 35 more convenient to apply said cover as it can not be put on wrong.

The registering mechanism is all secured to, and carried by, the cover 11 and is readily accessible when the cover is removed. The registering mechanism is supported by a main frame member of a form more clearly shown in Fig. 3. 40 This main frame member comprises a piece of metal bent to form an upper horizontal wall 18, a downwardly inclined wall 19 and a lower horizontal wall 20, said wall 20 terminating in a downwardly inclined end, 21. Two upwardly projecting flanges 22 are provided along the sides of the horizontal wall portion 18 and two side plates 23 are connected with the edges of the inclined wall 19 and extend upwardly and forwardly therefrom. The forward end of each side plate 23 has 50 a lug 24 provided thereon for engagement with a shoulder 25 which is formed by that portion of the cover lip 12 which extends around the corners and a short distance along the sides of the cover. The rear end 26 of the horizontal wall 18 is bent 55

upwardly and is engaged above a detent member 27 in the end of the cover 11 thus securing the main frame member to the cover 11. The main frame member is wide enough and long enough 5 to substantially fill the receptacle 10, thereby leaving a lower coin holding compartment 28 in said receptacle and an upper mechanism compartment 29 partly in the receptacle 10 and partly in the cover 11.

10 The cover 11 is provided, near one end, with a plurality of coin slots 30, each for the reception of a coin of predetermined denomination and dimension, and said cover is provided near the other end with a plurality of openings 31 through 15 which registering mechanism, of a form herein-after described, may be read. A sheet 32 of transparent material is preferably placed within the cover 11 so as to extend across the openings 31. In this disclosure I show and describe a bank 20 designed to receive coins of three different denominations, preferably five, ten and twenty-five cent pieces but obviously said bank may be constructed for the reception of a greater or less number of coins and for coins of different denomination and 25 size.

The registering mechanism comprises three registering wheels 33, 34 and 35, rotatably mounted side by side on a common shaft 36 which is supported by the side plates 23. Each wheel has 30 a cylindrical portion on the circumference of which is a strip 37, preferably of thin metal, upon which the amounts to be indicated or registered are displayed. These strips 37 are preferably 35 printed or embossed while flat and are drawn snugly around the peripheries of the wheels 33, 34 and 35 and have their ends 38 inserted within slots in said wheels and bent reversely within the rim portions of the wheels, as more clearly shown in Fig. 7. It will be understood that the line 40 where the two ends of these strips come together will be between two sets of figures. Ratchet wheels 39, 40 and 41 are made integral with, or are otherwise rigidly secured to, the respective 45 wheels 33, 34 and 35 and pawl members 42, 43 and 44 are provided for engaging with the respective ratchet wheels 39, 40 and 41. The pawl members 42, 43 and 44 are integral with wider slide members 45, 46 and 47 which rest slidably on the horizontal section 18. The plate section 18 has 50 three coin slots 48 provided therein directly below the coin slots 30 in the cover 11 and a downwardly extending guide and coin engaging lug 49 on the rear end of each slide 45, 46 and 47 is slidably disposed in the adjacent coin slot 48 and 55 is arranged to be engaged by a coin, as herein-after set forth, to move the slide forwardly. Obviously longitudinal movement of any one of the slide members 45, 46 and 47 toward the registering wheel will cause the pawl 42, 43 or 44 thereon to engage with one of the ratchet wheels and advance the registering wheel which is connected therewith. A spring is provided in connection with each slide 45, 46 and 47, for retracting the same. Each of these springs embodies a loop 50 supported on a lug 51 which is provided in the main frame member at the junction of the walls 19 and 20. One spring end 52 extends upwardly from each loop 50 and engages within a suitable notch 53 in the corresponding slide member. 60

70 The tips of the springs 52 which engage in the notches 53 are curved rearwardly on a gradual curve so that they will urge the slides rearwardly and exert a slight downward pressure but will not cause the pawls to bear hard on the ratchet 75 wheels.

The other spring end 54 of each loop 50 extends upwardly and bears against a circular friction and stop member 55 which is formed alongside of each ratchet wheel. The friction and stop member 55 has a stop shoulder 56 thereon which is arranged to abut against the end of the spring member 54 when the corresponding register wheel is in the zero or starting position. The friction of the spring 54 on the member 55 tends to prevent accidental movement of the attached register wheel. 10 In addition to this friction I also form a transverse hump or curve 57 in each spring member 54 for producing frictional engagement with the sides of the two register wheels between which the spring end projects. Slight depressions 58 are provided at intervals in the edges of the register wheels for the spring humps 57 to rest in for each registering position of each wheel. This helps to bring the registering wheels to the correct position each time they are advanced and helps to hold them in the correct position until they are again moved by the insertion of a coin.

A coin operated locking member 59 is mounted for relatively slight rocking movement just above the frame plate 18 and overlying the slides 45, 46 and 47. Lugs 60 on the sides of said locking member 59 are positioned within recesses 61 in the side flanges 22 of frame member 18 and form anchoring and pivot means for the locking member 59. Preferably the proportions of the locking member 59 and lugs 60 are made so that the locking member may be quickly and easily assembled in the frame by inserting first one lug and then the other and then inserting the frame in the cover plate so that the sides of the cover plate engage the ends of the lugs. The coin operated locking member 59 is provided with three coin slots 62, 63 and 64 of proper size and shape for the reception respectively of twenty-five, ten and five cent coins. The coin slots 62, 63 and 64 register with corresponding coin slots 30 in the cover plate 11. The rear edge of the locking member 59 is bent upwardly to afford an inclined portion 65 which is pressed to form a notch 65', preferably of arcuate or V shape, at the rear end of each slot 62, 63 and 64 with which the rear edge of a coin which is being inserted through the slot may engage, said inclined portions 65 being differently positioned longitudinally of the locking member and located at the ends of the coin slots 62, 63 and 64 which are of different length to correspond to the size of different coins. The front ends of the several coin slots 62, 63 and 64 are positioned substantially in the same line transversely of the locking member. The notches 65' in the inclined portions 65 and corresponding notches 49' in the downwardly extending lugs on the slides 45, 46 and 47 are preferably of arcuate or V shape so that only the corners of the coins will engage therewith. This avoids contact with the milling on the peripheral portions of the coins and results in much smoother operation. It should be noted that the milling on ten and twenty-five cent pieces terminates short of the corners of the coins. The forward end of the locking member 59 is provided with three downwardly extending pawls 66 for engagement within suitable recesses 67 in the slide members 45, 46 and 47 whereby the said slide members will be locked against forward movement except when the forward end of the locking member 59 is tilted up by pressure of a coin against the rear end thereof as the coin is inserted. The front end of the locking member 59 is yieldingly held down by engagement of the inclined front sides 66' of the pawls 66 with up- 75

wardly extending inclined lugs 67' which are formed from the metal that is punched out of the slides 45, 46 and 47 when the recesses 67 are made. It will be apparent that rearward pressure of the 5 spring members 52 on the slides will cause the inclined pawls 66 to tend to hold the forward end of the locking member down. An upwardly arched portion 68 is provided near the rear end of the locking member 59 and in the portion 10 through which the coin slots pass said arched portion affording better guiding means for the coins and strengthening the locking plate at the location where it is the most weakened by the cutting of the coin slots therein. A coin gripping member 70 preferably of thin sheet metal is secured to the inside of the cover 11 at the location of the coin slots 38 and is provided with resilient tooth like portions 69 which will engage with the flat sides of a coin and prevent the said coin from 20 being withdrawn after it has been partially inserted in the coin slots. This prevents the withdrawal of a coin which has been inserted far enough to operate the registering mechanism.

The registering wheels are each preferably 25 marked to register twenty coins and will repeat if more than twenty coins are passed through any one slot. No means are disclosed for keeping track of the number of repetitions. This makes it possible, without repeating on any of the register wheels, to register twenty-five cent pieces up to five dollars and ten-cent pieces up to two dollars and five-cent pieces up to one dollar. The zero or starting position for the register wheels is 30 between the first and last registration numbers 35 and the stop shoulder 56 is so positioned as to stop each registering wheel on the zero position. When the cover 11 is removed the registering wheels are exposed and may be operated with the fingers for the purpose of returning them to 40 the zero position. The ends of the pawls 42, 43 and 44 are always withdrawn clear of the ratchet teeth so that the ratchet wheels may be turned in either direction to re-set the register wheels.

In the operation of this registering bank it will 45 be understood that the register wheels will all be set at their zero position before the bank is used or each time it is emptied. When a coin of proper size is inserted into any one of the coin slots said coin will first engage with the inclined notched 50 wall 65 at the rear end of the locking member 59 and tilt the rear end of the locking member 59 down and the front end of said locking member up thus lifting pawls 66 out of recesses 67 and releasing the slides 45, 46 and 47. As the pawls 55 66 never rise entirely above the lugs 67' they will always block rearward movement of any of the slides when the front end of the locking member is thus raised. Further movement of the coin into the slot will move the slide 45, 46 or 47 with which 60 the coin engages, toward the register wheels, causing the pawl on the forward end of the slide which is thus moved to engage with the proper ratchet wheel and advance the register wheel one step, the raising of the front end of the locking 65 member permitting the pawl to raise slightly without bearing down on the wheel. As soon as the widest part of the coin has passed between the rear end of the slide and the rear end of the coin slot in the locking member 59, the spring pressure 70 on the slide will return said slide to its retracted position and snap the coin down into the coin receptacle. In this way each coin which is inserted into a coin slot will advance the corresponding register wheel one step and the register 75 wheel will register, up to the limit of its markings,

the total amount of the coins which have been inserted through the corresponding slot. After a register wheel has registered one complete revolution it will display the largest amount which is marked thereon and the zero marks will be the 5 next ones on said wheel. However, if another coin is inserted the wheel will be moved beyond the zero position and far enough to display the first or lowest amount marked thereon. In this way the registering wheel will repeat without showing 10 a zero if more than the number of coins which such wheel is designed to register are inserted, this being accomplished by inserting the zero marks between the first and last numbers which are only one space apart. 15

The coin operated locking member 59 will engage with and lock the slides 45, 46 and 47 against movement except at the time that a coin is being pressed through one of the coin slots, at which time the forward end of the locking member 59 will be raised clear of the slides. This prevents 20 operation of the registering devices in any way except by insertion of a coin of proper denomination.

The coin slots are of just large enough size to 25 pass the coins for which they are intended and the distance between the rear end of each slide 45, 46 and 47 and the corresponding rear wall 65 of the locking member 59 is made sufficiently less than the diameter of the coin for which it 30 is intended to insure enough movement to advance the corresponding register disc one division each time a coin is inserted. 35

It will be noted, Fig. 7, that the register wheels are centrally counterbored on one end, as at 55', and have small cylindrical hubs at the other end, as at 34', which fit into the counterbore on the adjacent register wheel. This makes the register wheels easy to align and hold, in assembling and the small bearing surface at the ends of the 40 hubs and near the centres of the wheels overcomes the tendency for one of the register wheels which is being moved, to carry adjacent register wheels along with it. It will also be noted in Fig. 1, that the hub 34' of the register wheel 35 abuts against the adjacent side plate 23 and holds 45 the wheel 35 away from said plate and that a lug member 75 is pressed upwardly near one edge of the frame portion 18 for the slide member 47 to engage with this lug member 75 makes it 50 possible in this construction to have all three slide members 45, 46 and 47 the same width. 55

The foregoing description and accompanying drawing clearly disclose a preferred embodiment of my invention but it will be understood that this disclosure is merely illustrative and that such changes in the invention may be made as are fairly within the scope and spirit of the following claims. 60

I claim:

1. In a coin operated registering money bank, a rectangular cover having sides thereon, a main frame member having upwardly extending side flanges arranged to fit snugly between the sides of said cover, said side flanges having oppositely disposed holes therein, and a locking plate disposed between said side flanges and having pivot lugs projecting sidewise from the edges thereof into said holes, whereby said locking plate is supported for rocking movement, the combined 65 width of said locking plate and length of one of said lugs being less than the distance between said side flanges permitting insertion of first one and then the other of said pivot lugs in said holes in assembly, said lugs being held within 70 75

said holes by the sides of said cover when the several parts are assembled.

2. In a coin operated registering money bank, a main frame member comprising a normally horizontal plate portion, a downwardly inclined portion at one end of said plate portion, normally horizontal guard portion at the lower end of said inclined portion, shallow side flanges extending upwardly from the sides of said plate portion, side plates extending forwardly from said inclined portion, a transverse axle member supported in said side plates, register wheels mounted on said axle member between said side plates, ratchet wheels on said register wheels, slide members slidable on said horizontal plate, pawls on said slide members engageable with said ratchet wheels, a locking plate pivotally supported for rocking movement above said slide plates, means on said locking plate engaging and locking said 20 slide members when said locking plate is in one position, and springs mounted on said main frame urging said slide members into retracted position.

3. In a coin operated registering money bank, a main frame member comprising a normally horizontal plate portion, a downwardly inclined portion at one end of said plate portion and a normally horizontal guard portion at the lower end of said inclined portion, shallow side flanges 30 extending upwardly from the sides of said plate portion, side plates extending forwardly from said inclined portion, a transverse axle member supported in said side plates, register wheels mounted on said axle member between said side plates, ratchet wheels on said register wheels, stop wheels on said ratchet wheels, slide members slidable on said horizontal plate, pawls on said slide members for engaging said ratchet wheels, said pawls being clear of said ratchet wheels when the slide members are retracted, 40 a locking plate pivotally supported for rocking movement above said slide plates and having means engaging and locking said slide members when said locking plate is in one position, and V-shaped springs supported on said main frame 45 one end of each of said springs being positioned between two adjacent register wheels in frictional contact therewith and engaging one of said stop wheels and the other end thereof engaging one of said slide members and exerting a retractile pressure thereon.

4. In a coin operated registering money bank, a main frame member comprising a normally hor-

izontal plate portion, a downwardly inclined portion at one end of said plate portion and a normally horizontal guard portion at the lower end of said inclined portion, shallow side flanges extending upwardly from the sides of said plate portion, side plates extending forwardly from said inclined portion, a transverse axle member supported in said side plates, a plurality of register wheels mounted on said axle member between said side plates, a cover extending over the top of said main frame and secured thereto, a slide member for each registering wheel, said slide members resting on said horizontal plate, a slide member locking plate positioned above and engageable with said slide members, said cover and said horizontal plate and said locking plate all having coin slots therein, pawl members integral with the forward ends of said slides engaging said register wheels, and spring means urging said slides into retracted position.

5. In a registering money bank, a register wheel, a spring pressed slide member positioned to advance said register wheel, said slide member having a recess therein and having upwardly projecting means provided with an inclined surface, and a pivoted locking plate having a pawl engageable within the recess in said slide for preventing movement of the slide, one side of said pawl being inclined and being engaged by the inclined surface means on said slide whereby the forward end of said locking member will be urged downwardly against said slide.

6. In a coin operated registering bank, a locking plate having a bent portion of inverted trough shape extending crosswise thereof and having coin slots therein extending through said trough shaped portion at right angles thereto, said inverted trough shaped portion affording additional bearing surface for the side faces of the coins.

7. In a coin operated registering money bank, two registering wheels rotatably mounted side by side, a stop wheel of less diameter than the registering wheels positioned between the registering wheels and secured to one of said registering wheels, said stop wheel having a stop shoulder thereon, and a spring pawl extending between said registering wheels and positioned to engage the stop wheel, said spring pawl having a resilient bend therein between the registering wheels frictionally engaging the sides of said registering wheels.

ROBERT B. HAYDEN.
